ARTICULATED OVERHEAD DOOR

David M. Robinson, New Britain, Conn., assignor
to The Stanley Works, New Britain, Conn., a
corporation of Connecticut

Application September 3, 1932, Serial No. 631,635

7 Claims. (Cl. 20—20)

This invention relates to doors, and particularly relates to doors of the type having a plurality of articulated panels or sections and adapted to be moved from a closed vertical position in the door-

5 way to an open overhead and generally horizontal position. As an instance of a use to which doors constructed in accordance with the present invention may be applied, reference may be had to automobile garages, but it is to be understood 10 that my improvements are not limited to that specific application, the improved structure being applicable to pier sheds, factories, et cetera.

An aim of the invention is to provide an improved and simplified door of this character which 15 is economical in construction, which may be quickly and easily installed, and which is efficient and durable in use.

A further aim of the invention is to provide an articulated door which, while being rugged and 20 durable in construction, may be very easily operated; that is, readily raised and lowered with a minimum amount of effort.

Other objects of the invention are to provide, in a door of this sort, improved means for bringing 25 the upper panel or section to closed position when the door is lowered; to provide an improved arrangement at small additional expense for retarding or snubbing the movement of the door as it approaches its full open position in order to 30 eliminate shocks and jars; and to provide an improved counterbalancing arrangement which may be nicely adjusted.

Other objects will be in part obvious, and in part pointed out more in detail hereinafter.

35 The invention accordingly consists in the features of construction, combination of elements and arrangement of parts which will be exemplified in the construction hereinafter set forth and the scope of the application of which will be 40 indicated in the appended claims.

In the accompanying drawings, wherein is shown, for illustrative purposes, one embodiment which the present invention may take,

45 Fig. 1 is an elevational view of the inside or rear of the door in closed position;

Fig. 2 is a side elevational view of one side of the arrangement, the door being shown in vertical section, this view being taken substantially on line 2—2 of Fig. 1;

50 Fig. 3 is a top plan view of the arrangement, certain parts being omitted;

Fig. 4 is a detail view in top plan of one of the track braces and parts associated therewith;

55 Fig. 5 is a side elevational view of what is shown in Fig. 4;

Fig. 6 is a detail view showing, in elevation, an edge of the lower panel of the door and the manner in which one of the extension springs is anchored at its lower end;

Fig. 7 is a side elevational view of the arrangement for swinging the upper panel against the door jamb when the door is brought to closed position; and

Fig. 8 is a rear view of what is shown in Fig. 7.

Referring to the drawings, there is shown there- 10 in so much of a garage or other structure as is necessary to illustrate one application of the invention, the structure having a doorway of suitable size provided with a frame which comprises two side posts P and a top lintel L. The door, 15 designated generally by the letter D, comprises a plurality of transversely extending panels or sections 10 of any suitable number and hingedly connected together along their adjacent longitudinal edges. The hinges for pivotally connecting the sections together may take any suitable form, they being designated by the numeral 11. In the present instance, the pintles 12 of the hinges at each side of the door extend beyond the marginal edge of the door and carry suitable 20 rollers 13. These rollers are adapted to travel in suitable tracks 14, there being two tracks, one at either side of the door opening. Adjacent each lower corner of the lowermost panel is fixed 25 a bracket 8 which carries a pin on which a roller 9 30 is journaled.

Each of the tracks has a vertically extending portion suitably secured to the rear face of a post P, as by means of track plates 15, a horizontal portion extending rearwardly in a plane adjacent the top of the doorway, and a curved portion connecting the upper end of the vertical portion and the forward end of the horizontal portion. The tracks, adjacent their rear ends, are connected together by a cross brace or angle iron 16, 40 and the overhead structure may be further braced by diagonally extending rods 17 in which are interposed suitable turnbuckle bodies 18. The rear end of the overhead structure may be supported in any suitable manner as by means of 45 chains 19 (see Fig. 2). As shown most clearly in Figs. 4 and 5, the forward end of the horizontal track section and the upper end of the curved track section are secured, as by means of bolts or rivets, to a track brace 20 which, in turn, is connected to a bracket 21 secured, as by means of screws 22, to a post P at a point above the top of the door opening. The brace 20 may be secured to the bracket 21 in any suitable manner, 50 as by means of rivets 23. The brace 20 is pro- 55

vided with an ear 24 and the bracket 21 is provided with another ear 25 and between these ears is positioned a pulley wheel 26, the same being journalled on a bolt 27. This wheel is positioned 5 forwardly of the horizontal section of the track and in a plane parallel to the plane of the door opening. Secured to each brace is an upper cable clip 28 having a sleeve portion 29. Also carried by each brace is a roller 30 which is disposed to 10 the inside of the vertical plane of the track and at a position below the inside edge of the pulley wheel. The purpose of these rollers will be described later. They are journalled on bolts 31.

As the door is moved from its full closed position 15 to an overhead position, the panels successively move into position where they are supported by the overhead horizontal track portion so that the effective weight of the door gradually decreases and, when the door is moved from open 20 to closed position, the reverse is true. In order to nicely counterbalance the door, there are provided two springs, preferably located one at each side of the doorway. The counterbalancing arrangements on the opposite sides of the doorway are 25 similar in construction and, therefor, a description of one will apply to the other. The extension spring, designated by the numeral 35, is vertically disposed behind the post P and is in the form of a coil the lower end of which is connected to an 30 anchor bracket 36 which, in turn, is connected to the lowermost track plate 15, as shown most clearly in Figs. 1 and 6. The upper end of the spring is adjustably connected, as hereinafter described more in detail, to a shackle 37 the upper 35 end of which is pivoted to the lower end of a sheave body 38 in which is journalled a pulley wheel 39 under which passes a cable or rope 40. One end of this cable is anchored to the upper cable clip 28, as shown in Figs. 4 and 5. In the 40 present instance, the upper end of the cable has secured to it a threaded member or screw 41 which extends through the knuckle 29 and the upper end of this screw receives the nuts 42. The opposite or lower end of the cable is connected in 45 a similar manner, (see Figs. 1 and 6) to a clip 43 secured to the lowermost panel of the door adjacent the lower corner thereof. The lower end of the cable is anchored to this clip by means of a nut 44. It will be seen from the drawings that 50 each rope passes under the wheel of the traveling sheave, then over the fixed pulley wheel 26, and then downwardly to the lower edge of the door, to which it is anchored. The vertical run of the cable between the door and the fixed pulley is 55 closely adjacent or tangential to the periphery of the roller 30.

For the purpose of adjusting the counterbalancing arrangement, either the effective length of the spring or the tension of the effective length of 60 the spring may be adjusted. To adjust or vary the effective length of the spring, the shackle 37 is adjustably associated with the upper end of the spring. In the present instance, this shackle is in the form of an inverted T-shaped member the 65 head of which is provided with openings 45 through which the coil is threaded, as shown most clearly in Fig. 5. By turning the shackle relative to the spring about the axis of the latter, the shackle is screwed onto the spring a greater or 70 less distance, depending upon the direction in which it is turned. In Fig. 5, the shackle is shown as being screwed onto the spring as far as it will go, there being provided on the stem of the shackle a stop 46 in order to guard against 75 the spring being shortened to such a great extent

that its efficiency is impaired. In order to adjust the tension of the effective length of the spring, the length of the cable may be adjusted by turning up either the bolts 42 on the upper end of the cable or the nut 44 on the lower end 5 of the cable.

It will be observed, from the drawings, that the curved portion of the track starts from a point below the top of the door opening. In order to swing the topmost panel forwardly into closed 10 position and against the door frame as the door completes its closing movement, and in order to swing the upper panel away from the door frame on initial upward movement of the door, there is provided, adjacent each side edge of the upper 15 panel, a cam and a fixed stud or pin adapted to cooperate therewith. The cams at the opposite sides of the top panel are similar in construction, and a description of one will apply to the other. Each of these cams is adjustably connected to the 20 top panel so as to accommodate panels of various heights and thicknesses. Each cam has a pair of cam members or surfaces between which is a cam groove which is curved upwardly and rearwardly with respect to the plane of the top 25 panel when the latter is closed. In the present illustrative disclosure of the invention, the cam is shown as having been formed of two pieces of rolled metal cut and bent to form. The front cam member, designated by the numeral 60, has a 30 turned-up flange 60' at one edge, and the rear or outer cam member, designated by the numeral 61, has a flange 61' to which the other flange 60' is secured, as by means of spot welding. Between the cam members 60 and 61 is a cam groove or 35 channel 62 which is open at its lower end and at the side of the door. The lower end of the rear wall 61 of the cam is bent or curved rearwardly, as at 63, so as to insure that the stud 70 will properly ride into the cam groove when the door 40 is brought to closed position. This stud or fixed pin 70 is here shown as being carried by a plate or bracket 71 adjustably connected, as by means of bolts 72, to the track. These bolts extend through elongated openings 72' in the bracket 45 so as to allow adjustment of the stud. It will be observed that the stud is horizontally disposed in a plane parallel to the door opening, and its free end extends inwardly towards the center of 50 the door opening. In order that cam devices of like construction may be used in connection with articulated doors having panels of varying heights and different thicknesses, the cams cooperating with the stud 70 are adjustably secured to the upper panel, as shown most clearly in Figs. 7 and 55 8. It will be seen from these figures that the cam is pivotally connected, as by means of a pin or pintle 64, to a cam bracket 65, the latter having a base 66 secured by screws 67 to the rear 60 face of the top panel. Extending rearwardly from one edge of this base is a flange 68 through which the pintle 64 extends. This flange has an arcuate slot 69 the center of curvature of which is coincident with the pintle 64. This slot 69 accommodates the stem of a bolt 69' carried by the 65 flanges of the cam. By changing the position of the bolt 69' in the slot 69, the angular relation between the cam and the plane of the top panel may be varied to suit conditions in the particular 70 installation.

For the purpose of supporting the upper end of the uppermost panel when the door is moved to horizontal position, there is provided adjacent each side edge of the upper panel, a pivoted arm 75 75 to the upper free end of which is fixed a pin

71 on which is journalled a roller 78 adapted to travel in the track. In the present instance, the lower end of the arm 75 is shown as being hinged on a pintle 79 supported by the flange 68 and a second flange 80 on the cam bracket 65.

From the foregoing description, taken in connection with the accompanying drawings, it will be observed that when it is desired to open the door to its raised position, it may be given an upward pull and then the spring will automatically complete the opening movement of the door. As the door starts to rise, the outer cam members 61 will wipe along the pins 70, thus causing the upper end of the uppermost panel to swing rearwardly until the door has been raised to such position that the pin leaves the cam groove 62. When the door has been raised to such an extent that the upper panel is horizontally disposed, the normally upper portion of that panel is supported on the pivoted arms 75 and the free ends of these arms are, of course, supported by the tracks through the rollers 78. As the door rises, the traveling sheave, under the tension of the extension springs, will move downwardly so that the force of the springs will gradually decrease as the successive panels ride onto the horizontal portions of the tracks. If the door is brought to full open position with more force than is necessary, those portions of the cables in front 30 of the stationary rollers 30 will be brought against those rollers so that the movement of the door is snubbed, so to speak, and this snubbing action is taken up by the extension springs 35 which thus act as buffers. Thus the strains and stresses which would result if the door were thrown to full open position against fixed stops are taken care of by the tension springs themselves without the expense of providing separate buffers or snubbers. The rollers 30 also prevent the cables from being pulled from the fixed pulleys when the door is thrown to full open position. To lower the door, the forward edge thereof is moved forwardly and pulled downwardly and, after the door has started, it will automatically move to practically closed position, further downward movement of the door being taken care of by the extension springs. As the door approaches its closed position, the cam devices will ride into operative relation to the fixed pins 70 and the front cam members 60 will wipe along these pins, thereby causing the upper end of the upper panel to swing forwardly and against the door jamb or frame.

It will further be seen from the foregoing description, that, in accordance with the present invention, there is provided an improved articulated overhead door arrangement which is characterized by its simplicity, economy, ruggedness, and durability in construction and arrangement, by the ease and facility with which the parts may be assembled and adjusted, and by its effectiveness in operation, the door being movable to open and closed position with safety and with but little effort on the part of the operator.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the in-

vention herein described and all statements of the scope of the invention which, as a matter of language, might be said to fall therebetween.

I claim as my invention:

1. In an overhead door construction, a pair of tracks each having a vertical section, a horizontal section and a curved connecting portion; an articulated door comprising a plurality of hingedly connected sections guided by said tracks and movable from a vertical closed position to an overhead and generally horizontal position; and counterbalancing means at each side of the door, each of said counterbalancing means including a fixed overhead pulley, a cable anchored at its upper end and passing over said pulley and connected at its other end to the lower end of the door, said cable having a depending loop between its anchored upper end and said pulley, a traveling sheave supported by said loop, a coiled tension spring having one end adjustably connected to said traveling sheave and its other end fixed adjacent the lower end of the track, means for adjusting the length of said cable to regulate the operative spring tension, and means associated with said sheave for selectively engaging the various coils of said spring to regulate the effective length thereof.

2. In an overhead door construction, a pair of tracks each having a vertical section, a horizontal section and a curved connecting portion; an articulated door comprising a plurality of hingedly connected sections guided by said tracks and movable from a vertical closed position to an overhead and generally horizontal position; and counterbalancing means at each side of the door, each of said counterbalancing means including a fixed overhead pulley, a cable anchored at its upper end and passing over said pulley and connected at its other end to the lower end of the door, said cable having a depending loop between its anchored upper end and said pulley, a traveling sheave supported by said loop, a coiled tension spring anchored at its lower end adjacent the lower end of the track, and a shackle pivotally connected to said traveling sheave and adapted to be screwed varying extents into the coils of the spring whereby the operative length of the spring may be regulated as required.

3. In an overhead door construction, a pair of tracks each having a vertical section, a horizontal section and a curved connecting portion; an articulated door comprising a plurality of hingedly connected sections guided by said tracks and movable from a vertical closed position to an overhead and generally horizontal position; and counterbalancing means at each side of the door, each counterbalancing means including a fixed pulley positioned forwardly of the horizontal section of the track and disposed in a plane parallel to the plane of the door opening, a cable secured at one end to the door adjacent the lower end of the latter and passing over said pulley, an extension spring associated at one end with said cable and fixed at its other end, and a fixed roller immediately below the point at which the cable passes onto said pulley, said roller being positioned behind said cable and arranged so that when the door is thrown to full open position said cable will engage thereagainst and said extension springs will act as buffers.

4. In an overhead door construction, a pair of tracks each having a vertical section, a horizontal section and a curved connecting portion; an articulated door comprising a plurality of

- hinged sections guided by said tracks and movable from a vertical closed position to an overhead and generally horizontal position; a cam device adjacent each side edge of the upper panel and rigidly fixed on the rear face thereof, each of said cam devices comprising an inner cam member and an outer cam member, the cam groove therebetween being curved upwardly and rearwardly, said cam groove being open at its lower end, and a pair of fixed studs one for each cam device, said studs being adapted to engage in the respective cam grooves when the door is closed.
5. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and rigidly mounted to the rear face thereof, said cam having a cam groove curved upwardly and rearwardly, means for adjustably securing said cam to the top panel, and a fixed stud adapted to be received by said cam groove when the door is moved to closed position whereby the upper panel is swung towards the door opening.
10. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and rigidly mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.
15. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.
20. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.
25. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.
30. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.
35. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.

an overhead and generally horizontal position; a cam adjacent one side edge of the upper panel and mounted to the rear face thereof, said cam having a cam groove curved upwardly and rearwardly, means for pivotally mounting said cam whereby the same may be angularly adjusted relative to the top panel, means for securing said cam in adjusted positions and against movement relative to the door, and a fixed stud adapted to be received by the cam groove when the door is lowered, whereby said upper panel is swung to closed position against the door frame.

7. In an overhead door construction, a pair of tracks each having a vertical section, a horizontal section, and a curved connecting portion; an articulated door comprising a plurality of hinged connected sections guided by said tracks and movable from a vertical closed position to an overhead and generally horizontal position; a cam adjacent one side edge of the upper panel and mounted to the rear face thereof, said cam having a cam groove curved upwardly and rearwardly, a cam bracket secured to the rear face of the upper panel, a pivot pin connecting said cam to said bracket, said bracket having an arcuate slot, a bolt carried by said cam extending through said slot whereby said cam may be secured in adjusted position relative to the top panel, a fixed stud adapted to engage in said cam groove when the door is closed, an arm pivoted to said bracket, and a roller carried by the upper free end of said arm and traveling in the associated track.

DAVID M. ROBINSON. 35
